STEREOTYPE PLATE CASTING MACHINE

Frank A. Foster, Melrose Park, Ill., assignor to
The Goss Printing Press Company, Chicago,
Ill., a corporation of Illinois

Application November 15, 1946, Serial No. 709,951

3 Claims. (Cl. 22--2)

1

This invention relates to stereotype plate casting machines for casting recesses in the back of a cylindrical or semi-cylindrical stereotype plate.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations, and improvements herein shown and described.

The accompanying drawings, referred to herein and constituting a part hereof, illustrate one embodiment of the invention, and together with the description, serve to explain the principles of the invention.

Of the drawings:

Fig. 1 is a vertical cross-sectional view of a stereotype plate casting machine embodying the present invention, taken along line 1—1 of Fig. 3;

Fig. 2 is a perspective view of a recess forming bar shown separated from other parts of the plate casting machine of Fig. 1;

Fig. 3 is a horizontal cross-sectional view taken along line 3—3 of Fig. 1 with a cast plate and matrix in position in the machine;

Fig. 4 is a cross-sectional view taken along line 4—4 of Fig. 1;

Fig. 5 is a view partly in side elevation and partly in cross section of the plate casting machine shown in the other figures; and

Fig. 6 is a perspective view of an insert member forming a part of the invention.

With the advent of high speed printing, it has been found desirable to subject stereotype plates to circumferential tension. This is done by securing the leading edge of the stereotype plate to the plate cylinder and by imposing a circumferential tension on the trailing edge of the plate. The patents to Crafts 2,047,357, dated July 14, 1936, Foster 2,047,364, dated July 14, 1936, and Worthington 2,236,230, dated March 25, 1941, show typical mechanism for imposing circumferential tension on a stereotype plate. It is important, in high speed printing, that this tension be imposed in order that the plate at all times will fit tightly against the plate cylinder and in order to compensate for deformation due to possible flow of metal due to the pressure between the plate and form cylinders. The use of circumferential tension also counteracts the effect of centrifugal force which is considerable in high speed machines.

2

The object of the present invention is to provide a casting box which will cast recesses in the back of the stereotype plate, into which recesses suitable tension applying means may engage when the plate is on the plate cylinder.

More specifically, the invention provides slideable bars on the core of the usual casting box in a stereotype plate casting machine, which bars carry dies to provide the proper recesses in the inner surface of the finished plate. The recess forming bars are formed with inclined edges to cooperate with correspondingly inclined surfaces of grooves in the core of the casting box forming a dovetailed joint, so that the bars may be moved longitudinally of the core, but cannot fall out in a radial direction, from their grooves. The recess forming bars are connected to the core for limited movement in their respective grooves, and are also connected to the collar of the casting mechanism which pushes the finished plate along the core to delivery position, the connections of the bars being such that the finished plate and bars are first pushed along the core in delivering, and thereafter movement of the bars is prohibited and movement of the plate is continued to place the plate in position to be removed from the machine.

The recess forming bars are of tapered formation being slightly wider at the top than at the bottom, said formation being accomplished by providing a straight edge for the bars nearer the parting bar of the casting apparatus, and an inclined opposite edge, so that as the finished plate is being delivered, the recess forming bars become somewhat free in their grooves in the core as they move with respect thereto, and move away from the leading edge of the plate recess, relieving the considerable pressure of the cooled plate on the bar prior to final delivering. The die portions of the recess forming bars are tapered from large at bottom to slightly smaller at the top so that when the bars and plate are relatively moved during the delivery of the plate, the latter may be easily removed from the casting machine.

It will be understood that the foregoing general description and the following detailed description as well are exemplary and explanatory of the invention but are not restrictive thereof. Referring now in detail to the preferred embodiment of the invention illustrated in the accompanying drawings, the stereotype plate casting machine there illustrated is in its main features of a known type, as shown in my Patent No. 2,100,003, granted November 23, 1937. The

mechanism comprises standards 10 supporting a core 11 for casting a cylindrical plate; it will be evident, however, that this invention may also be applied to the casting of a semi-cylindrical plate.

Cooperating with the core 11 is the usual two part drag composed of parts 12 and 13 hinged together by hinges 14, the two parts of the drag being swingable about the hinges by the conventional handle (not shown) and lockable in closed position by another handle, not shown.

The core of the embodiment here illustrated is tiltable to and from casting position by the handle 17. A parting strip 20 is provided for positioning the matrix 21, and a parting bar 22 is provided on the core 11 to form the vertical walls of the casting chamber corresponding to the gap in a cylindrical stereotype plate 23. A collar 25 is provided surrounding the core 11 and having a reduced portion 26 to serve as a bottom for the casting chamber and also to eject the plate 23 when it is cast by pushing it along core 11. The mechanism for automatically operating collar 25 to eject the plate when core 11 is tilted by means of handle 17 comprises pintles 27 fixed to and projecting from opposite sides of collar 25. Pivotedly mounted on these pintles are arms 29 and 30, the lower ends of these arms being pivoted on pintles 31 and 32 which are mounted in the frame members 10.

Coming now to the features constituting the present invention, the core 11 is provided with a pair of longitudinal tapered grooves 35 spaced to either side of parting bar 22, and these grooves receive the tapered recess forming bars 36. The grooves 35 in the core are provided with inclined edges 37 to cooperate with the oppositely inclined edges of bars 36 to form a dovetailed joint as shown in Fig. 3, so that the bars may be moved longitudinally with respect to core 11 but will be held in their respective grooves.

As shown the bars 36 are each formed with die portions 40 which extend radially outwardly from the core and into the casting chamber between the core 11 and the matrix 21. These die portions are adapted to form suitable recesses in the inner surface of plate 23 to receive plate tension mechanism. As best shown in Fig. 2 of the drawings, die portions 40 are tapered, being somewhat wider at the bottom than at the top, formed with a straight edge 41 toward the leading edge of the plate and an inclined opposite edge 42 for a purpose which will presently be set forth. The bars 36 are also of tapered formation, being wider at the top than at the bottom, having straight edges 44 toward the edges of the plate and inclined opposite edges 45. Grooves 35 are correspondingly tapered to tightly receive the bars 36. Thus, when the bars 36 are moved upwardly with respect to core 11 in their grooves 35, they become loose therein and may be forced toward their edges 45 by the pressure of the cooled plate upon die portions 40.

As best shown in Figs. 1 and 5 of the drawings, the bars 36 are mounted for limited relative motion with respect to core 11, each being provided with a screw 46 threaded therethrough, the reduced ends 47 of which extend into deeper recesses or grooves 48 in the core. The enlarged heads 49 of screws 46 are positioned in longitudinal slots 50 in portion 26 of collar 25.

With the construction shown it will be apparent that when the casting box is opened and the core 11 is tilted for delivery of the plate 23, the collar 25 will force the plate and the bars 36

(because their die portions are embedded in the plate) upwardly along the core until ends 47 of screws 46 reach the upper limit of grooves 48. At this point further travel of bars 36 is prohibited, but collar 25 continues ejecting the plate until the heads 49 of screws 46 abut the lower edges of slots 50. During this period of relative motion between the plate and bars 36 the former is pushed outwardly to a position where the plate may then be grasped by the workman and finally removed from the casting mechanism.

When the core 11 is tilted back to casting position, bars 36 will be returned to their lower positions by the engagement of screw heads 49 with the upper edges of slots 50, and will be accurately positioned for the next casting operation by their tapered edges in grooves 35.

As best shown in Figs. 4, 5 and 6 of the drawings, an insert 52 is positioned adjacent each recess forming bar 36 in suitable grooves in the core 11 and collar 25 in order to provide a tight seal and prevent molten metal from going down into the crevices of the sliding joints. The inserts are closely fitted to both the collar and the bars, and each has a straight side 53 to permit the collar to slide and an inclined side 54 to permit the bar to slide and to relieve tension on the plate when the core is in delivery position.

The invention in its broader aspects is not limited to the specific mechanisms shown and described but departures may be made therefrom within the scope of the accompanying claims without departing from the principles of the invention and without sacrificing its chief advantages.

What is claimed is:

1. A machine for casting stereotype plates with recesses in the back thereof comprising a core, a jacket surrounding the core in spaced relationship thereto to provide a cylindrical casting space with an open end, a collar surrounding the core for closing the other end of said casting space said collar being longitudinally movable with respect to said core for moving a plate in said casting space toward said open end, a margin bar extending radially across said casting space along the length thereof to provide separated and spaced ends of a stereotype plate cast in the casting space, said core having a pair of grooves extending longitudinally thereof said grooves being positioned one on either side of said margin bar substantially parallel and adjacent thereto, a recess forming bar in each said groove slidably mounted therein and extending throughout the length of said casting space, each said bar having a die portion thereon extending longitudinally the entire length of said casting space and radially into said casting space to form recesses in the plate cast therein, said die portions being longitudinally tapered with the greater width at the bottom, and said recess forming bars being longitudinally tapered with the greater width at the top, said core grooves being tapered correspondingly to said bars, and means interconnecting said core, collar and bars permitting limited relative longitudinal movement of said collar and bars with respect to said core and with respect to each other including a limited longitudinally slidable connection between each bar and the collar, and a limited longitudinally slidable connection between each bar and the core, each said connection comprising a radially extending projection received in a longitudinally extending recess.
2. A machine for casting stereotype plates with

recesses in the back thereof comprising a core, a jacket surrounding the core in spaced relationship thereto to provide a cylindrical casting space with an open end, a collar surrounding the core for closing the other end of said casting space said collar being longitudinally movable with respect to said core for moving a plate in said casting space toward said open end, a margin bar extending radially across said casting space along the length thereof to provide separated and spaced ends of a stereotype plate cast in the casting space, said core having a pair of grooves extending longitudinally thereof said grooves being positioned one on either side of said margin bar substantially parallel and adjacent thereto, a recess forming bar in each said groove slidably mounted therein and extending throughout the length of said casting space, each said bar having a die portion thereon extending longitudinally the entire length of said casting space and radially into said casting space to form recesses in the plate cast therein, said die portions being longitudinally tapered with the greater width at the bottom, and said recess forming bars being longitudinally tapered with the greater width at the top, said core grooves being tapered correspondingly to said bars, said die portions being longitudinally tapered with the greater width at the bottom, and said recess forming bars being longitudinally tapered with the greater width at the top, said core grooves being tapered correspondingly to said bars, and a radially extending projection on each said recess forming bar extending toward said collar and said core, said collar and core each being formed with longitudinally extending recesses to receive said extensions, whereby limited relative longitudinal movement is permitted of said collar and said bars with respect to said core and with respect to each other.

3. A machine for casting stereotype plates with recesses in the back thereof comprising a core, a jacket surrounding the core in spaced relationship thereto to provide a cylindrical casting space with an open end, a collar surrounding the core for closing the other end of said casting space said collar being longitudinally movable with respect to said core for moving a plate in said casting space toward said open end, a margin bar extending radially across said casting space along

45

the length thereof to provide separated and spaced ends of a stereotype plate cast in the casting space, said core having a pair of grooves extending longitudinally thereof said grooves being positioned one on either side of said margin bar substantially parallel and adjacent thereto, a recess forming bar in each said groove slidably mounted therein and extending throughout the length of said casting space, each said bar having a die portion thereon extending longitudinally the entire length of said casting space and radially into said casting space to form recesses in the plate cast therein, said die portions being longitudinally tapered with the greater width at the bottom, and said recess forming bars being longitudinally tapered with the greater width at the top, said core grooves being tapered correspondingly to said bars, said die portions and said bars being formed with edges nearer said margin bar which are substantially parallel thereto and inclined opposite edges giving said tapered formation to said portions and bars, and means interconnecting said core, collar and bars permitting limited relative longitudinal movement of said collar and bars with respect to said core and with respect to each other including a limited longitudinally slidable connection between each bar and the collar, and a limited longitudinally slidable connection between each bar and the core, each said connection comprising a radially extending projection received in a longitudinally extending recess.
